(57) **ABSTRACT**

A golf club head with a hosel hole cover that helps improve the performance of the golf club head is disclosed. More specifically, the present invention relates to a golf club head having a hosel hole cover at a bottom portion of an interchangeable connection system that not only provides improved performance of the golf club head by strategically utilizing an existing opening to adjust the weighting of a golf club head, but it also improves the aerodynamics of the golf club head by eliminating undesirable recesses that could be detrimental to the aerodynamics of a golf club head.

GOLF CLUB HEAD WITH HOSEL HOLE COVER

CROSS-REFERENCE TO RELATED APPLICATIONS

The present application is a Continuation-In-Part (CIP) of U.S. patent application Ser. No. 17/338,513, filed on Jun. 3, 2021, which is a CIP of U.S. patent application Ser. No. 17/196,676, filed Mar. 9, 2021, the disclosure of which are both incorporated by reference in their entirety.

FIELD OF THE INVENTION

The present invention relates generally to a golf club head with a hosel hole cover that helps improve the performance of the golf club head. More specifically, the present invention relates to a golf club head having a hosel hole cover at a bottom portion of an interchangeable connection system that not only provides improved performance of the golf club head by strategically utilizing an existing opening to adjust the weighting of a golf club head, but it also improves the aerodynamics of the golf club head by eliminating undesirable recesses that could be detrimental to the aerodynamics of a golf club head.

BACKGROUND OF THE INVENTION

Improving the aerodynamics of a golf club head has always been one of the ways golf club designers attempt to improve the performance of a golf club head. U.S. Pat. No. 4,754,974 to Kobayashi back in 1987 illustrated one of the earliest attempts to improve the performance of a golf club head by focusing on the aerodynamics. Kobayashi attempts to create a surface structure on a golf club head to produce a turbulent boundary layer in the air on the outer surface of the head body.

Although the aerodynamics of a golf club head may be a crucial component in it's overall performance, there are numerous other factors that also helps contribute to improving the overall performance of a golf club head; some of which could even come with some detriment to the aerodynamics of the golf club head. U.S. Pat. No. 6,368,230 to Helmstetter et al. filed in 2000 illustrates one of these innovations as it relates to a golf club that creates a removable hosel system, allowing the club and shaft to be releasably attached to one another. This invention not only made it significantly easier for golfers to try different club and head combinations in their golf club, it also paved the way for subsequent technological advancements in the industry relating to golf club adjustability.

U.S. Pat. No. 7,887,431 to Beach et al., filed in 2008 illustrates further improvements upon the previously discussed invention by creating a releasable shaft system that is also capable of altering the loft and/or lie angle of the golf club head without resorting to traditional bending of the shaft.

However, both the Helmstetter et al. and Beach et al. invention requires access to the golf club from the bottom of the sole into the hosel region via a sole attachment opening, which could adversely affect the aerodynamics of the golf club head. In addition to the above, this attachment opening that is required to facilitate the interchangeability of the shaft hosel system can also be leveraged to manipulate the center of gravity (CG) of the golf club head by installing a weighting member in this attachment opening.

U.S. Pat. No. 10,668,336 to Kingston illustrates an attempt to take advantage of the attachment opening to help manipulate the weighting of the golf club head. More specifically, Kingston teaches a weight plug sized to fit within, and at least partially fill, the heel-side attachment opening. Kingston although capable of utilizing this existing attachment opening for weighting purposes, does so via a complicated system requiring multiple components, often requiring multiple threads that make it complicated to install and uninstall. Moreover, Kingston fails to recognize the ability to improve the aerodynamics of the golf club head by addressing the negative effects of the attachment opening on the aerodynamics of the golf club head.

Hence, based on the above, it can be seen that there is a need in the art for an improved hosel hole cover that can easily adjust the weighting and CG of the golf club head all while improving the aerodynamics of the golf club head.

BRIEF SUMMARY OF THE INVENTION

One aspect of the present invention is a golf club head comprising of a body portion, further comprising of a crown portion, a sole portion, a heel portion, and a toe portion. The golf club head has a hosel region located near a heel portion of the golf club head, wherein the hosel region further comprises of an upper end having a releasable hosel mechanism, a lower end having a hosel hole, a hosel hoe cover, and a retention mechanism. The hosel hole itself further comprises of one or more non-threaded recessed undercuts along a side wall of the hosel hole. The hosel hole cover is adapted to substantially cover the entirety of an internal surface of the hosel hole. The retention mechanism is adapted to secure the hosel hole cover to the golf club head, wherein the retention mechanism further comprises of one or more non-threaded protrusions. The one or more non-threaded protrusions are adapted to engage the one or more non-threaded recessed undercuts to secure the hosel hole cover to the golf club head.

In another aspect of the present invention is a golf club head comprising of a body portion, further comprising of a crown portion, a sole portion, a heel portion, and a toe portion. The golf club head has a hosel region located near a heel portion of the golf club head, wherein the hosel region further comprises of an upper end having a releasable hosel mechanism, a lower end having a hosel hole, and a hosel hole cover. The hosel hole cover is adapted to substantially cover the entirety of an external surface of the hosel hole, and the hosel hole cover further comprises a receptacle opening, wherein the receptacle opening has a surface area of between about 55 mm² to about 300 mm².

In another aspect of the present invention is a golf club head comprising of a body portion, further comprising of a crown portion, a sole portion, a heel portion, and a toe portion. The golf club head has a hosel region located near a heel portion of the golf club head, wherein the hosel region further comprises of an upper end having a releasable hosel mechanism, a lower end having a hosel hole, a hosel hoe cover, and a retention mechanism. The hosel hole itself further comprises of one or more non-threaded recessed undercuts along a side wall of the hosel hole. The hosel hole cover is adapted to substantially cover the entirety of an internal surface of the hosel hole. The retention mechanism is adapted to secure the hosel hole cover to the golf club head, wherein the retention mechanism further comprises of one or more non-threaded protrusions. The one or more non-threaded protrusions are adapted to engage the one or more non-threaded recessed undercuts to secure the hosel

hole cover to the golf club head. The hosel hole cover further comprises a receptacle opening, adapted to receive the retention mechanism, the receptacle opening has a surface area of between about 55 mm² to about 300 mm². The engagement member is only adapted to rotate 90 degrees.

In another aspect of the present invention, a polymeric damping member, contacting both the hosel hole and the hosel hole cover, at least partially separating the hosel hole cover from the hosel hole.

In another aspect of the present invention, at least a portion of the hosel hole cover is deformable, and the hosel hole cover bends to allow access to the hosel hole by disengaging at least one of the one or more non-threaded protrusions from the one or more non-threaded recessed undercuts.

These and other features, aspects and advantages of the present invention will become better understood with reference to the following drawings, description and claims.

BRIEF DESCRIPTION OF THE DRAWINGS

The foregoing and other features and advantages of the invention will be apparent from the following description of the invention as illustrated in the accompanying drawings. The accompanying drawings, which are incorporated herein and form a part of the specification, further serve to explain the principles of the invention and to enable a person skilled in the pertinent art to make and use the invention.

FIG. 1 of the accompanying drawings shows a bottom sole side perspective view of a golf club head in accordance with an exemplary embodiment of the present invention;

FIG. 2 of the accompanying drawings shows an enlarged view of a hosel region of a golf club head as shown by circular region 2 shown in FIG. 1;

FIG. 3 of the accompanying drawings shows an exploded perspective view of a hosel region of a golf club head in accordance with an embodiment of the present invention;

FIG. 4 of the accompanying drawings shows a partial cross-sectional view of a hosel region of a golf club head wherein the hosel hole cover is in an unlocked position in accordance with an embodiment of the present invention;

FIG. 5 of the accompanying drawings shows a partial cross-sectional view of a hosel region of a golf club head wherein the hosel hole cover is in a locked position in accordance with an embodiment of the present invention;

FIG. 6a of the accompanying drawings shows an exploded perspective view of a hosel region of a golf club head in accordance with an alternative embodiment of the present invention;

FIG. 6b of the accompanying drawings shows a partial cross-sectional view of a hosel region of a golf club head where the hosel hole cover is in an unlocked position in accordance with an alternative embodiment of the present invention;

FIG. 6c of the accompanying drawings shows a partial cross-sectional view of a hosel region of a golf club head wherein the hosel hole cover is in a locked position in accordance with an alternative embodiment of the present invention;

FIG. 7a of the accompanying drawings shows a bottom sole perspective view of a golf club head in accordance with another alternative embodiment of the present invention;

FIG. 7b of the accompanying drawings shows an enlarged view of a hosel region of a golf club head shown in FIG. 7a by enlarging the same circular region 2 shown in FIG. 1;

FIG. 7c of the accompanying drawings shows an exploded perspective view of a hosel region of a golf club head in accordance with another alternative embodiment of the present invention;

5 FIG. 7d of the accompanying drawings shows a partial cross-sectional view of a hosel region of a golf club head where the hosel hole cover is in a locked position in accordance with another alternative embodiment of the present invention;

10 FIG. 8a of the accompanying drawings shows an enlarged view of a hosel region of a golf club head shown in accordance with an even further alternative embodiment of the present invention;

15 FIG. 8b of the accompanying drawings shows an exploded perspective view of a hosel region of a golf club head in accordance with an even further alternative embodiment of the present invention;

20 FIG. 8c of the accompanying drawings shows a rear view of a hosel region of a golf club head where the hosel hole cover is in an unlocked position in accordance with an even further alternative embodiment of the present invention;

25 FIG. 8d of the accompanying drawings shows a rear view of a hosel region of a golf club head wherein the hosel hole cover is in a locked position in accordance with an even further alternative embodiment of the present invention;

30 FIG. 8e of the accompanying drawings shows a partial cross-sectional view of a hosel region of a golf club head wherein the hosel hole cover is in a locked position in accordance with an even further alternative embodiment of the present invention;

35 FIG. 9a of the accompanying drawings shows an exploded perspective view of a hosel region of a golf club head in accordance with another alternative embodiment of the present invention;

40 FIG. 9b of the accompanying drawings shows a partial cross-sectional view of a hosel region of a golf club head wherein the hosel hole cover is in an unlocked position in accordance with another alternative embodiment of the present invention;

45 FIG. 9c of the accompanying drawings shows a partial cross-sectional view of a hosel region of a golf club head wherein the hosel hole cover is in a locked position in accordance with another alternative embodiment of the present invention;

50 FIG. 10a of the accompanying drawings shows an exploded perspective view of a hosel region of a golf club head in accordance with another alternative embodiment of the present invention;

55 FIG. 10b of the accompanying drawings shows a rear internal view of a hosel region of a golf club head wherein the hosel hole cover is in an unlocked position in accordance with another alternative embodiment of the present invention;

60 FIG. 10c of the accompanying drawings shows a rear internal view of a hosel region of a golf club head wherein the hosel hole cover is in a locked position in accordance with another alternative embodiment of the present invention;

65 FIG. 11a of the accompanying drawings shows an exploded perspective view of a hosel region of a golf club head in accordance with another alternative embodiment of the present invention;

70 FIG. 11b of the accompanying drawings shows a partial cross-sectional view of a hosel region of a golf club head wherein the hosel hole cover is in an unlocked position in accordance with another alternative embodiment of the present invention;

installed in the hosel hole in accordance with an even further alternative embodiment of the present invention;

FIG. 22b of the accompanying drawings shows an exploded perspective view of the two piece hosel hole cover in accordance with an even further alternative embodiment of the present invention;

FIG. 22c of the accompanying drawings shows an exploded view of the hosel hole cover and the hosel hole in accordance with an even further alternative embodiment of the present invention;

FIG. 22d of the accompanying drawings shows a cross-sectional view of the hosel hole cover and the hosel hole in accordance with an even further alternative embodiment of the present invention;

FIG. 23a of the accompanying drawings shows an exploded view of a hosel hole cover and the hosel hole in accordance with another alternative embodiment of the present invention;

FIG. 23b of the accompanying drawings shows another exploded view of a hosel hole cover and the hosel hole in a different orientation in accordance with another alternative embodiment of the present invention;

FIG. 23c of the accompanying drawings shows a perspective view of a hosel hole cover in an open position installed in the hosel hole in accordance with another alternative embodiment of the present invention;

FIG. 23d of the accompanying drawings shows a partial cross-sectional view of a hosel hole cover in a closed position together with the hosel hole in accordance with an alternative embodiment of the present invention;

FIG. 24a of the accompanying drawings shows an exploded perspective view of a hosel hole cover and a hosel hole in accordance with another alternative embodiment of the present invention;

FIG. 24b of the accompanying drawings shows a partial cross-sectional view of a hosel hole cover and the hosel hole in a closed position in accordance with another alternative embodiment of the present invention;

FIG. 24c of the accompanying drawings shows a partial cross-sectional view of a hosel hole cover and the hosel hole in an open position in accordance with another alternative embodiment of the present invention;

FIG. 25a of the accompanying drawings shows a perspective view of a hosel hole cover in an opened position together with the hosel hole in accordance with an even further alternative embodiment of the present invention;

FIG. 25b of the accompanying drawings shows a partial cross-sectional view of a hosel hole cover and the hosel hole in a closed position in accordance with an even further alternative embodiment of the present invention;

FIG. 25c of the accompanying drawings shows a partial cross-sectional view of a hosel hole cover and the hosel hole in an open position in accordance with an even further alternative embodiment of the present invention;

FIG. 26a of the accompanying drawings shows a perspective view of a hosel hole cover in an open position together with a hosel hole in accordance with another alternative embodiment of the present invention;

FIG. 26b of the accompanying drawings shows a partial cross-sectional view of a hosel hole cover in a closed position together with a hosel hole in accordance with another alternative embodiment of the present invention;

FIG. 26c of the accompanying drawings shows a partial cross-sectional view of a hosel hole cover in an open position together with a hosel hole in accordance with another alternative embodiment of the present invention;

FIG. 27a of the accompanying drawings shows a perspective view of a hosel hole cover in an open position together with a hosel hole in accordance with an alternative embodiment of the present invention;

FIG. 27b of the accompanying drawings shows a partial cross-sectional view of a hosel hole cover in a closed position together with a hosel hole in accordance with an alternative embodiment of the present invention;

FIG. 27c of the accompanying drawings shows a partial cross-sectional view of a hosel hole cover in an open position in accordance with an alternative embodiment of the present invention;

FIG. 28a of the accompanying drawings shows an exploded perspective view of a hosel hole cover in accordance with a further alternative embodiment of the present invention;

FIG. 28b of the accompanying drawings shows an internal perspective view of a hosel hole cover in an open position in accordance with an alternative embodiment of the present invention;

FIG. 28c of the accompanying drawings shows an internal perspective view of a hosel hole cover in a closed position in accordance with an alternative embodiment of the present invention;

FIG. 28d of the accompanying drawings shows a partial cross-sectional view of a hosel hole cover together in a hosel hole in accordance with an alternative embodiment of the present invention; and

FIG. 28e of the accompanying drawings shows a partial cross-sectional view of a hosel hole cover together in a hosel hole in accordance with an alternative embodiment of the present invention.

DETAILED DESCRIPTION OF THE INVENTION

The following detailed description describes the best currently contemplated modes of carrying out the invention. The description is not to be taken in a limiting sense, but is made merely for the purpose of illustrating the general principles of the invention, since the scope of the invention is best defined by the appended claims.

Various inventive features are described below, and each can be used independently of one another or in combination with other features. However, any single inventive feature may not address any or all of the problems discussed above or may only address one of the problems discussed above. Further, one or more of the problems discussed above may not be fully addressed by any of the features described below.

FIG. 1 of the accompanying drawings shows a perspective sole view of a golf club head 100 in accordance with an exemplary embodiment of the present invention showing the golf club head 100 in an upside down orientation. The golf club head 100 is further comprised of a crown portion 102 (shown as the underside in FIG. 1), the sole portion 104, a heel portion 106, and a toe portion 108. The golf club head 100 in accordance with the present invention may generally have a hosel region 110 located the heel portion 106 of the golf club head 100. At the upper end of the hosel region 110 is a releasable hosel mechanism 112 that allows the golf club head 100 to be releasably attached to different shafts using an attachment screw (not shown), sometimes even allowing for adjustments to the loft, lie, and face angle of the golf club head, all without departing from the scope and content of the present invention. More information relating to the technology behind the releasable hosel mechanism 112 can be

found in commonly owned U.S. Pat. No. 10,272,298 to Zimmerman et al., the disclosure of which is incorporated by reference in its entirety. Additionally, FIG. 1 of the accompanying drawings shows the hosel hole cover 114 with a retention mechanism 116 adapted to cover up the entirety of an internal surface of the hosel hole 118, located at a lower end of the hosel region 110 opposite the releasable hosel mechanism 112. Finally, FIG. 1 of the accompanying drawings also highlight a circular region 2, to which an enlarged view of the hosel region 110 of the golf club head 100 may be shown in more detail.

FIG. 2 of the accompanying drawings shows an enlarged view of the hosel region 210 of a golf club head 200 in accordance with an exemplary embodiment of the present invention as highlighted by circular region 2 shown in FIG. 1. In this enlarged view, we can see that the hosel hole cover 214 has a substantially oval shape that matches the external surface of the hosel hole 218 that is also oval shaped, and the same hosel hole cover 214 is attached to the golf club head 200 via a retention mechanism 216 shown here. The retention mechanism 216, although appearing as a mere screw head in FIG. 2, in actually an advanced attachment mechanism that is aimed at reducing the complexity of installing and removing the hosel hole cover 214 from the hosel hole 218. In order to illustrate the relationship between the various components, and the mechanism of retention, FIG. 3 of the accompanying drawings is provided below.

FIG. 3 of the accompanying drawings shows an exploded view of the hosel region 310 in accordance with an exemplary embodiment of the present invention. This exploded view of the hosel region 310 shows how the three major components, the hosel hole 318, the hosel hole cover 314, and the retention mechanism 316, fit together. Referring to the hosel hole 318 shown in this exploded view in FIG. 3, we can see that the hosel hole 318 further comprises of one or more non-threaded recessed undercuts 320a and 320b that is formed along a side wall of the hosel hole 318. A first non-threaded recessed undercut 320a is formed towards the rear inside surface of the hosel hole 318, and adapted to engage a first non-threaded protrusion 321a via an attachment opening (not shown in this view) in the rear portion of the hosel hole cover 314. A second non-threaded recessed undercut 320b, is formed towards one of the side walls of the hosel hole 318 that is 90 degrees offset from the first non-threaded recessed undercut 320a, and is adapted to engage a second non-threaded protrusion 321b via a second attachment opening 322b in the hosel hole cover 314. A third non-threaded recessed undercut (not shown here in this view, but is 180 offset from the second recessed undercut 320b and 90 degrees offset from the first threaded recessed undercut 320a in the opposite direction as the second recessed undercut 320b) is adapted to engage a third non-threaded protrusion 321c via a third attachment opening 322c in the hosel hole cover 314.

In addition to the above, FIG. 3 of the accompanying drawings also shows a male ledge 326 at the bottom of the hosel hole cover 314 the engages a corresponding female ledge (not shown in FIG. 3) at the bottom of the hosel hole 318 to further provide structural stability to the hosel hole cover 314 for it to be securely installed in the hosel hole 318.

A careful analysis of the relationship above makes clear the relationship between the three components hosel hole 318, hosel hole cover 314, and the retention mechanism 316 more clear. In summary, the present invention provides a unique non-threaded retention mechanism for securing the hosel hole cover 314 to the hosel hole 318 by first engaging the male ledge 326 with the female ledge. Once the hosel

hole cover 314 has achieved its desired location within the hosel hole 318, the retention mechanism 316 is inserted through a receptacle opening 325 in the hosel hole cover 314. The receptacle opening 325 is shaped in a way to receive the retention mechanism 316 that forces the orientation of the retention mechanism 316 to a specific starting orientation to initiate the install. This rotation is generally a 90 degree rotation during the insertion process. Once the hole cover 314 receives the retention mechanism 316, a 180 degree rotation will allow the main non-threaded protrusion 321a to protrude out of an attachment opening 322a (not shown in FIG. 3) to engage the main non-threaded recessed undercut 320a. The other secondary protrusions 321b, and 321c, although capable of engaging corresponding non-threaded recessed undercuts 320b and 320c (not shown in FIG. 3) via openings 322b, and 322c to provide additional points of engagement for the hosel hole cover 314 into the hosel hole 318, it is not necessary. In fact, in the preferred alternative embodiment of the present invention, the secondary protrusions 321b and 321c only engage the openings 322b and 322c only as a means to secure the retention mechanism 316 to the hosel hole cover 314. It should be noted that it is critical to recognize here that the retention mechanism 316 is only adapted to rotate 180 degrees from its unlocked position towards its locked position. This feature is critical to the proper function of the present invention because it dramatically reduces the complexity of the installation and removal of the hosel hole cover 314 compared to a traditional threaded screw, which is important to the end user. The rotation of the retention mechanism 316 is generally accomplished via a six point star-shaped hex-lobular pattern screw head, however, numerous other types of rotating screw mechanism may be used without departing from the scope and content of the present invention so long as it is able to provide a rotational force to the retention mechanism 316.

Before moving onto cross-sectional views of the present invention, it is worthwhile to discuss the aerodynamic benefits of the present invention. The aerodynamics of golf clubs have always been an area of interest for golf club designers, and voids in the bottom of the sole of the golf club head can generally alter the aerodynamic properties of the golf club head. Hence is it worth noting here that the shape and design of the hosel hole cover 314 is absolutely critical to the aerodynamic performance of the golf club head, and thus critical to the present invention that aims to improve the overall performance of the golf club head. The present invention, recognizing that the hosel hole 318 could greatly affect the aerodynamic performance of the golf club head, has found that an oversized hosel hole 318 is detrimental to the aerodynamic performance of the golf club head by reducing its ability to achieve maximum clubhead speed. However, on the flip side, the current research has also showed that too smooth of a sole, with little to no holes or openings into the sole is incapable of tripping the boundary layer of flow around the golf club head, which ironically also reduces clubhead speed. Hence, in order to maximize the aerodynamics of the current design of a golf club head, the current invention, the hosel hole cover 314 incorporates a receptacle opening 325 that has a surface area that is neither too large nor too small. More specifically, it can be said that the receptacle opening 325 in accordance with the present invention, may generally have a surface area between about 55 mm² to about 300 mm², more specifically between about 65 mm² to about 200 mm², and most preferably about 90 mm².

11

FIG. 4 of the accompanying drawings shows a partial cross-sectional view of a hosel region 410 of a golf club head in accordance with an exemplary embodiment of the present invention in the starting or unlocked orientation, as previously described. As you can see in this partial cross-sectional view, none of the non-threaded protrusions previously discussed are visible, because they have not been rotated to engage the non-threaded recessed undercuts. In this partial cross-sectional view, the first attachment opening 422a is shown for the first time to be an attachment opening at the rear surface of the hosel hole cover 414, placed directly adjacent to the first non-threaded recessed undercut 420a. In addition to the above, this partial cross-sectional view of the hosel region 410 shown in FIG. 4 is also capable of illustrating the relationship between the male ledge 426 and the female ledge 428, both of which have previously been explained as the initial alignment of the hosel hole cover 414 with the hosel hole.

FIG. 5 of the accompanying drawings is more interesting, as it shows a partial cross-sectional view of a hosel region 510 of a golf club head in accordance with an exemplary embodiment of the present invention in the installed or locked orientation. In this view, it can be seen that the first non-threaded protrusion 521a is now rotated into an orientation to allow it to protrude out from the first attachment opening 522a, to engage the first non-threaded recessed undercut 520a. This engagement of the first non-threaded protrusion 521a (not shown in FIG. 5) with the first non-threaded recessed undercut 520a secures the hosel hole cover 514 to the hosel hole 518 near the hosel region 510. FIG. 5 also shows how additional attachment openings could work in conjunction with the first attachment opening 522a to help further secure the hosel hole cover 514 to the hosel hole 518. Although the present embodiment of the present invention incorporates three sets of protrusions, attachment openings, and recessed undercuts, any other number of sets of these may be used, including but not limited to one set, two sets, three sets, four sets, or any number of sets all without departing from the scope and content of the present invention.

Another feature to note in the partial cross-sectional views of the hosel region 510 is that the retention mechanism used to secure the hosel hole cover 514 to the golf club head is completely different from the threaded screw 530 that holds the golf club head itself to the shaft itself within the releasable hosel mechanism. As previously discussed, more information regarding the releasable hosel mechanism may be found in the commonly owned U.S. Pat. No. 10,272,298 to Zimmerman et al., the disclosure of which is once again incorporated by reference in its entirety.

FIGS. 6a through 6c of the accompanying drawings show exploded and cross-sectional views of a hosel region 610 in accordance with an alternative embodiment of the present invention. This alternative embodiment shown in FIGS. 6a through 6c is very similar to the embodiment previously discussed, except in this embodiment the shapes of the various components are tweaked slightly to ensure better interface between the various components. Similar to previous discussions, the hosel hole 618 in this embodiment shows one or more non-threaded recessed undercuts 620a, 620b, and 620c (not shown in FIG. 6). These one or more non-threaded recessed undercuts 620a, 620b, and 620c (not shown in FIG. 6) are adapted to receive one or more non-threaded protrusions 621a, 621b, and 621c on the retention mechanism 616, via one or more attachment openings 622a, 622b, and 622c on the hosel hole cover 614. Finally, as previously discussed, the hosel hole cover has a

12

male ledge 626 that is adapted to engage a female ledge 628 in the hosel hole 618 to retain the hosel hole cover 614 to the hosel hole 618.

FIGS. 7a through 7d of the accompanying drawings shows a golf club head 700 in accordance with an alternative embodiment of the present invention. FIG. 7a shows this alternative embodiment of the present invention wherein the hosel region 710 of the golf club head 700 also has a hosel hole cover 714 located within a hosel hole 718. However, in this alternative embodiment of the present invention, the retention mechanism 716 is not visible once installed, leaving on the receptacle opening 725 visible. The cross-sectional area of this receptacle opening 725, in order to achieve the improved aerodynamics previously discussed, is also between about 55 mm² to about 300 mm², more specifically between about 65 mm² to about 200 mm², and most preferably about 90 mm².

FIG. 7b showing an exploded view of the golf club head 700 allows the previously invisible retention mechanism 716 to be shown more clearly. Based on this exploded view, we can see that the retention mechanism 716 is a tab based mechanism, wherein the non-threaded protrusion 721 engages a non-threaded recessed undercut 720 within the hosel hole 718 to secure the hosel hole cover 714 to the hosel hole 718. Based on this exploded view, we can see that the engagement mechanism 716 is not a rotational type of engagement mechanism like the previous embodiment. In fact, it is a deflection based retention mechanism 716 that deflects out of the way when subjected to an external force to snap into the non-threaded recessed undercut 720 to retain the hosel hole cover 714.

The external force to deflect the retention mechanism 716 can be applied via any elongate member to be inserted into the hosel hole cover 714 through a receptacle opening 725. The insertion of the elongate member will cause the non-threaded protrusion to deflect away from the non-threaded recessed undercut 720, allowing the hosel hole cover 714 to be moved in and out of the hosel hole 718.

FIGS. 8a through 8e of the accompanying drawings illustrates a hosel region 810 of a golf club head 800 in accordance with a further alternative embodiment of the present invention. In this alternative embodiment of the present invention shown in FIGS. 8a through 8e, a different type of retention mechanism 816 is used to secure the hosel hole cover 814 to the hosel hole 818. The enlarged exploded view of the hosel region 810 shown in FIG. 8b provides an easy to understand illustration of the various components used in this embodiment of the present invention. Although an initial glance at this alternative embodiment may appear complex, it actually operates very similar to the previous discussion relating to 180 degree rotation of the engagement mechanism 816 previously discussed and utilizes several similarly named components. However, in this embodiment of the present invention, the non-threaded protrusions 821b and 821c are not preinstalled on the retention mechanism 816, but rather are additional pieces that move with the rotation of the engagement mechanism 816. Additionally, the degree of rotation for this embodiment is only 90 degrees to turn from a locked position to an unlocked position. It should be noted that although the reduced amount of rotation of less than 360 degrees is critical to the proper functionality of the present invention to preserve simplicity, the actual number of degree of rotation can be either 90 degrees or 180 degrees all without departing from the scope and content of the present invention.

Diving into more detail relating to this embodiment, it can be seen from FIG. 8b that the current embodiment, similar

to previous embodiments, has two non-threaded recessed undercuts **820b** and **820c** (not shown) within the hosel hole **818** that are adapted to engage the non-threaded protrusions **821b** and **821c** via attachment openings **822b** and **822c** in the hosel hole cover **814**. These non-threaded protrusions **821b** and **821c** are not attached to the retention mechanism **816** directly, but rather engage tabs **823b** and **823c** that translates rotational movement of the retention mechanism **816** into linear movements in the non-threaded protrusions **821b** and **821c**. FIGS. **8c** through **8d** provides a rear internal view of the retention mechanism **816** in both the unlocked and locked position respectively, further illustrating the concept explained above. In FIG. **8c**, when the retention mechanism is in an unlocked position, we can see that the tabs **823b** and **823c** that protrude out from the retention mechanism **816** does not engage the non-threaded recessed undercuts **820b** and **820c** directly when the retention mechanism **816** is rotated. Rather, tabs **823b** and **823c** are adapted to engage slots **832b** and **832c** in the non-threaded protrusions **821b** and **821c**; and when the engagement mechanism **816** is rotated to a locked position as shown in FIG. **8d**, the rotational movement of the retention mechanism **816** engages the tabs **823b** and **823c** with the slots **832b** and **832c** to retain the hosel hole cover **814** to the hosel hole **818**, which can also be seen in the cross-sectional view of the hosel region **810**.

FIGS. **9a** through **9c** of the accompanying drawings shows a hosel region **910** of a golf club head **900** in accordance with a further alternative embodiment of the present invention. This embodiment of the present invention, similar to previous embodiments, incorporates rotational movement of the retention mechanism **916** to move one or more non-threaded protrusions **921a**, **921b**, and **921c** to engage one or more non-threaded recessed undercuts **920a**, **920b**, and **920c** (not shown in FIG. **9**) in the hosel hole **918**, via one or more attachment openings **922a**, **922b**, and **922c** in the hosel hole cover **914**. The receptacle opening **925** in the hosel hole cover **914** works in the same way as previous described, and is adapted to receive the retention mechanism **916** by guiding it into a starting/unlocked orientation, and rotating the retention mechanism **916** 180 degrees will secure the hosel hole cover **914** to the hosel hole **918**. The major difference in this embodiment compared to previous embodiments of the present invention is that the hosel hole cover **914** further comprises of a internal ledge **927** in addition to the male ledge **926** to help secure the hosel hole cover **914** to the hosel hole **918**. Additionally, this embodiment of the present invention creates the first non-threaded recessed undercut **920a** that is of a different shape and protrudes out more than the previous embodiments.

FIG. **10a** through **10c** of the accompanying drawings shows hosel region **1010** of a golf club head **1000** in accordance with a further alternative embodiment of the present invention. In this alternative embodiment, the non-threaded recessed undercut **1020a** is formed via a spring clip **1040** within the hosel hole **1018** and the non-threaded protrusion **1021** is formed via a rotatable member **1042** that engages the retention mechanism **1016**. The hosel hole cover **1014** shown here is essentially the same as previous embodiments, and the attachment opening **1022b** shown here is oversized, in order to accommodate the need for the rotatable member **1042** to move and engage the spring clip **1040**. Using an oversized rotatable member **1042** to engage a spring clip **1040** may be preferred in this embodiment of the present invention in order to provide a more robust solid retention mechanism, although at the expense of adding some additional components. FIG. **10b** of the accompanying

drawings shows the relationship between the spring clip **1040** and the rotatable member **1042** together with the retention mechanism **1016** in an unlocked position, where FIG. **10c** of the accompanying drawings shows the same components in a locked position. In an alternative embodiment of the present invention, a spring member (not shown) may be added to return the rotatable member **1042** to a natural locked position to enhance the usability of the present invention.

FIGS. **11a** through **11c** of the accompanying drawings illustrate the hosel region **1110** of a golf club head **1100** in accordance with an even further alternative embodiment of the present invention. In this alternative embodiment of the present invention, the retention mechanism **1116** helps retain the hosel hole cover **1114** within the hosel hole **1118** by rotating along a plurality of pins **1144b** and **1144c** that protrude out from attachment openings **1122b** and **1122c** within the hosel hole cover **1114**. In an alternative embodiment of the present invention, the plurality of pins **1144b** and **1144c** could be one long pin without departing from the scope and content of the present invention. The rotation of the retention mechanism **1116** engages a flap **1146** within the hosel hole **1118** to help retain the hosel hole cover **1114** within the hosel hole **1118**. FIG. **11b** shows the hosel region **1110** in an unlocked position, while FIG. **11c** shows the hosel region in a locked position.

FIGS. **12a** through **12c** of the accompanying drawings shows a hosel region **1210** of a golf club head in accordance with an even further alternative embodiment of the present invention. In this further alternative embodiment of the present invention, the hosel hole cover **1214** is attached to go on top of the hosel hole **1218** without the need of a retention mechanism. In fact, the hosel hole cover **1214** in this embodiment is merely retained in the hosel hole **1218** via glue, instead of an advanced retention mechanism as illustrated in previous embodiments. Since the glued in hosel hole cover **1214** is not going to be releasable, the receptacle opening **1225** need to be large enough to accommodate the threaded screw **1230** to attach to a shaft via the releasable shaft mechanism **1212**. Hence, it is worth reiterating here that in order to preserve the aerodynamic benefit of the hosel hole cover **1214**, the receptacle opening **1225** may have a surface area of between about 55 mm² to about 300 mm², more specifically between about 65 mm² to about 200 mm², and most preferably about 90 mm².

FIG. **13a** through **13c** of the accompanying drawings shows a hosel region **1310** of a golf club head in accordance with an even further alternative embodiment of the present invention. In this further alternative embodiment of the present invention, the hosel hole cover **1314**, once again, does not incorporate an additional component of a retention mechanism, but rather utilizes the existing threaded screw **1330** that is used to attach to a shaft to also secure the hosel hole cover **1314** to the hosel hole **1318**. The receptacle opening **1325**, similar to all previous embodiments, needs to have the right surface area and the right size to promote the aerodynamic benefits previously discussed.

FIGS. **14a** through **14c** of the accompanying drawings shows a hosel region **1410** of a golf club head in accordance with an even further alternative embodiment of the present invention. In this further alternative embodiment of the present invention, the hosel hole cover **1414** is secured to the hosel hole **1418** using one or more non-threaded protrusions **1421** located on the hosel hole cover **1414** to engage one or more non-threaded recessed undercuts **1420** located within the hosel hole **1418** to secure the hosel hole cover **1414** to the hosel hole **1418**. The non-threaded protrusions **1421** in

15

this embodiment differ from previous embodiments that incorporate this feature, as these protrusions do not move, and are not linked to a retention mechanism. Hence, in order to ensure the hosel hole cover 1414 stays within the hosel hole 1418, additional bonding agent such as glue may be added to enhance this bond without departing from the scope and content of the present invention. Finally, the receptacle opening 1425 in this embodiment, as previous discussion have already indicated, has the same surface area as previously discussed.

FIGS. 15a through 15c of the accompanying drawings shows various views of a hosel hole cover 1514 in accordance with an alternative embodiment of the present invention, where a polymeric damping member 1540 is added as an intermediary between the hosel hole cover 1514 and the hosel hole 1518. More specifically, FIG. 15a of the accompanying drawings shows a hosel hole cover 1514 with a non-threaded protrusion 1521 and a male ledge 1526, which work in conjunction to help secure the hosel hole cover 1514 to the hosel hole 1518 as previously described. However, new in this embodiment is the addition of the polymeric damping member 1540, which wraps around the perimeter portion of the hosel hole cover 1514 at the junction with the hosel hole 1518. This polymeric damping member 1540, is generally made from a polymeric material, capable of absorbing any tolerancing issues between the hosel hole cover 1514 and the hosel hole 1518, as well as absorb any vibration dampening that occurs when the golf club head impacts a golf ball.

FIG. 15b of the accompanying drawings shows a reverse view of the same hosel hole cover 1514 from an internal point of view, allowing the polymeric damping member 1540 to be shown more clearly. Seeing the polymeric damping member 1540 from this view shown in FIG. 15b illustrates how it take the form of a gasket, and surrounds the entirety of the external interface between the hosel hole cover 1514 and the hosel hole 1518, which improves the effectiveness of the polymeric damping member 1540.

Finally, FIG. 15c of the accompanying drawings shows a partial cross-sectional view of the hosel hole cover 1514 being installed within the hosel hole 1518 together with the polymeric damping member 1540 acting as an intermediary between the two components. In addition to illustrating the polymeric damping member 1540, this cross-sectional view also illustrates the interface between the various components, which works similar to previous embodiments that does not contain the polymeric damping member 1540.

FIGS. 16a through 16c of the accompanying drawings shows various views of a hosel hole cover 1614 and a hosel hole 1618 having a polymeric damping member 1640 to help dampen any potential vibration between the two components. However, unlike the previous embodiment where the polymeric damping member 1540 (shown in FIG. 15) is located around a perimeter of the holes hole cover 1514 (shown in FIG. 15), the polymeric member 1640 in this embodiment is located inside the hosel hole 1618 instead, without departing from the scope and content of the present invention.

FIG. 16a shows an exploded perspective view of the bottom hosel region of a golf club head, allowing the inside of the hosel hole 1618 to be shown by moving the hosel hole cover 1614. In this exploded perspective view, the polymeric damping member 1640 can be shown in the upper rear portion of the hosel hole 1618, adapted to engage the hosel hole cover 1614.

FIG. 16b of the accompanying drawings shows another exploded perspective view of the bottom hosel region of a

16

golf club head, this time from an opposite angle, allowing the internal workings of the hosel hole 1618 to be shown with the polymeric damping member 1640. In this alternative angle, we can see that the polymeric damping member 1640 may be installed in an opening in the hosel hole 1618 and adapted to engage the non-threaded protrusion 1621 of the hosel hole cover 1614.

FIG. 16c of the accompanying drawings shows a partial cross-sectional view of the hosel hole cover 1614 being installed within the hosel hole 1618 together with the polymeric damping member 1640 acting as an intermediary between the two components. Once again, in this cross-sectional view shown in FIG. 16c, we see that the polymeric damping member 1640 is not in the shape of a gasket, but rather as a cushion located at the upper rear portion of the hosel hole 1618. The polymeric damping member 1640 shown here engages the non-threaded protrusion 1621, as previously mentioned.

FIGS. 17a and 17b of the accompanying drawings shows various views of a hole cover 1714 and a hosel hole 1718 having an even further different type of polymeric damping member 1740 than previously shown. More specifically, as shown in FIG. 17a, the polymeric damping member 1740 in accordance with this embodiment of the present invention is located at the bottom portion of the hosel hole cover 1714, adapted to engage a threaded screw 1730 (shown in FIG. 17b) to provide the vibration dampening.

FIG. 17b of the accompanying drawings shows a partial cross-sectional view of the hosel hole cover 1714 being installed within the hosel hole 1718, illustrating the relationship of the components that make up this present invention. As it can be seen from FIG. 17b, as the hosel hole cover 1714 is being compressed into the hosel hole 1718 the entire hosel hole cover 1714 moves downward as the ledge 1742 of the non-threaded protrusion 1721 engages the geometry of the hosel hole 1718. The downward movement of the hosel hole cover 1714 compresses the polymeric damping member 1740 against the head of the threaded screw 1730 to provide the vibration dampening desired.

FIGS. 18a through 18d of the accompanying drawings show various views of a multi-piece hosel hole cover 1814, formed out of a cover piece 1814a and a base piece 1814b, in accordance with a further alternative embodiment of the present invention. The cover piece 1814a is adapted to partially engage the base piece 1814b, after which the entire hosel hole cover 1814 can slidably engage the hosel hole 1818. Once the hosel hole cover 1814 engages the hosel hole 1818, the retention of the entire hosel hole cover 1814 is achieved by fully engaging the cover piece 1814a with the base piece 1814b. The exploded view of the multi-piece hosel hole cover 1814 shown in FIG. 18a and FIG. 18b shows how the cover piece 1814 further comprises a retention mechanism 1816 that engages a threaded bore in the base piece 1814b without the need for a thread, utilizing several same non-threaded recessed undercuts 1820 that has been previously discussed. The cross-sectional view of the multi-piece hosel hole cover 1814 shown in FIGS. 18c and 18d shows the engagement of the various pieces in an installed and uninstalled position, further illustration the relationship of the various components.

FIGS. 19a through 19d of the accompanying drawings show various views of a multi-piece hosel hole cover 1914, formed out of a cover piece 1914a and a base piece 1914b, in accordance with an even further alternative embodiment of the present invention. In this embodiment, the base piece 1914b, together with the cover piece 1914a, slides into the hosel hole 1918 in a “partial” or “open” position. Once the

entire hosel hole cover 1914 assembly is fully engaged in the hosel hole 1918, a rotation of the cover piece 1914a rotatably secures the entire hosel hole cover 1914 assembly within the hosel hole 1918. In this embodiment of the present invention, the securing of the hosel hole cover 1914 to the hosel hole 1918 can be achieved by a mere 180° rotation of the cover piece 1914a, which may be preferred for its simplicity.

FIGS. 20a through 20c of the accompanying drawings show various view of hosel hole cover 2014 is formed out of a flexible polymer material that can bend away at the bottom of the hosel hole cover 2014 to allow access to the hosel hole 2018 without the need of any extraneous tools. In the current exemplary embodiment of the present invention, the deformable hosel hole cover 2014 may be made out of a deformable polymeric material, however, in alternative embodiments of the present invention, the deformable hosel hole cover 2014 made be made out of other types of deformable material so long as it can bend away to provide access to the holes hole 2018 all without departing from the scope and content of the present invention. In this embodiment of the present invention, the hosel hole cover 2014 comprises a non-threaded protrusion 2021 adapted to engage a non-threaded recessed undercut 2020 in the closed position to prevent inadvertent disengagement. If access to the hosel hole 2018 is necessary, the hosel hole cover 2014 in this embodiment can merely be pried away using one's fingernails at the top of the hosel hole cover 2014, allowing the pliable non-threaded protrusion 2021 to be pried away from the non-threaded recessed undercut 2020 without departing from the scope and content of the present invention.

FIGS. 21a through 21d of the accompanying drawings show various views of hosel hole cover 2114 that is formed out of a flexible polymer material that can bend away at the bottom of the hosel hole cover 2114 to allow access to the hosel hole 2118. However, this embodiment of the present invention differs from the embodiment previous described in FIGS. 20a through 20c in that the present invention utilizes a receptacle 2116 disguised as a tool opening of a retention mechanism (see 116 in FIG. 1) that merely provides an engagement point to deform the hosel hole cover 2114. It should be noted that the receptacle 2116, although visually looks like it should receive a tool that rotates to provide engagement and disengagement of the hosel hole cover 2114 from the hosel hole 2118, actually only serves to provide a point of leverage allowing one to more easily deform the hosel hole cover 2114. The retention of the hosel hole cover 2114 in this embodiment is achieved by an interference between one of the several pliable non-threaded protrusions 2121 with one of the several non-threaded recessed undercuts 2120 similar to what is previously shown.

FIGS. 22a through 22d of the accompanying drawings show various views of a two piece hosel hole cover 2214 that has one deformable component and one rigid component. More specifically, the hosel hole cover 2214 is further comprised out of a deformable cover piece 2214a and a rigid base piece 2214b. The rigid base piece 2214b shown in this embodiment is generally made out of a rigid polymeric material, however, in alternative embodiments, the rigid base piece 2214b may be made out of a metallic material, a composite material, or any other types of material so long as it has more structural rigidity than the deformable cover piece 2214a, all without departing from the scope and content of the present invention. The deformable cover piece 2214a in this embodiment functions similarly to the one piece hosel hole cover 2114 show in FIG. 21 in that it bends and deforms out of place when a tool is used to engage the

receptacle 2216 to provide access to the hosel hole 2218. The non-threaded protrusions 2221 in the deformable cover piece 2214a engages the non-threaded recessed undercuts 2220 to retain the cover piece 2214a of the hosel hole cover 2214, while the rigid base piece 2214b also utilizes a similar mechanism for retention. Separating the hosel hole cover 2214 into a deformable cover piece 2214a and a rigid base piece 2214b allows for more structural rigidity in the hosel hole cover 2214 while still providing the flexibility of a deformable cover piece 2214a.

FIGS. 23a through 23d of the accompanying drawings show various views of a hosel hole cover 2314 in accordance with a further alternative embodiment of the present invention. Similar to previous embodiments, the hosel hole cover 2314 in this embodiment is made out of a deformable material that can bend away at portions that is not fixedly attached to the hosel hole. In this embodiment of the present invention the hosel hole cover 2314 fixedly attaches to the hosel hole 2318 at one end of the hosel hole cover via a plurality of circular protrusions 2351 that engages a plurality of circular recesses 2350. The engagement of the plurality of circular protrusions 2351 fixedly, but not permanently, attaches the hosel hole cover 2314 all while allowing the other end of the hosel hole cover 2314 to be peeled away allowing access to the hosel hole 2318 itself. When installed, the non-threaded protrusions 2321 engages the non-threaded recessed undercuts 2320 to hold the hosel hole cover 2314 in place, which can be disengaged via the bending of the hosel hole cover 2314 using a tool that engages the receptacle 2316.

FIGS. 24a through 24c of the accompanying drawings show various views of another deformable hosel hole cover 2414 in accordance with an alternative embodiment of the present invention adapted to cover the hosel hole 2418. In this embodiment of the present invention, the hosel hole cover 2414 comprises a plurality of non-threaded protrusions 2421 that are adapted to engage complimentary non-threaded recessed undercuts 2420 to help allow the hosel hole cover 2414 to conceal the hosel hole 2418. The hosel hole cover 2414 in this embodiment deforms and bends away at the bottom of the hosel hole 2418 when a tool 2460 is inserted into the receptacle 2416 to allow the top portion of the hosel hole cover 2414 to bend away from the hosel hole 2418.

FIGS. 25a through 25c of the accompanying drawings show various views of another deformable hosel hole cover 2514 in accordance with an alternative embodiment of the present invention adapted to cover the hosel hole 2518. In this embodiment of the present invention, similar to previous embodiments, the hosel hole cover 2518 comprises a plurality of non-threaded protrusions 2521 that are adapted to engage complimentary non-threaded recessed undercuts 2520 to allow the hosel hole cover 2514 to conceal the hosel hole 2518. The hosel hole cover 2514 in this embodiment differs from previous embodiments in that it deforms upwards instead of downwards to allow access to the hosel hole 2518 by placing the fixed portion of the hosel hole cover 2514 near the top of the hosel hole 2518, while the moving portion of the hosel hole cover 2514 is now shifted towards the bottom of the hosel hole 2518. Finally, a tool 2560 can be used to engage the receptacle 2516 just as previous embodiments to deform and open the hosel hole cover 2514.

FIGS. 26a through 26c of the accompanying drawings show various views of another deformable hosel hole cover 2614 in accordance with another alternative embodiment of the present invention adapted to cover the hosel hole 2618.

In this embodiment of the present invention, the receptacle **2616** of the deformable hosel hole cover **2518** may be oversized, with the engagement portion of the receptacle **2616** recessed within the receptacle **2616** to be more discrete. The hosel hole cover, **2614** still have several non-threaded protrusions **2621** that engage with non-threaded recessed undercuts **2620** in the hosel hole **2618** to provide the engagement mechanism.

FIGS. **27a** through **27c** of the accompanying drawings show various views of another deformable hosel hole cover **2714** in accordance with an even further alternative embodiment of the present invention that is adapted to cover the hosel hole **2718**. In this embodiment of the present invention, the receptacle **2716** has the engagement portion recessed within the receptacle, **2716**, but the opening created by having that recessed engagement portion can be further covered up by a secondary flap **2717** that is also made out of the same deformable material as the hosel hole cover **2714**. The remainder of the hosel hole cover **2714** works similarly in utilizing non-threaded protrusions **2721** to engage with non-threaded recessed undercuts **2720** in the hosel hole **2718** to provide the engagement mechanism.

FIGS. **28a** through **28e** of the accompanying drawings show various views of another hosel hole cover **2814** in accordance with another embodiment of the present invention. In this embodiment of the present invention, the hosel hole cover **2814** is formed out of two pieces, a base portion **2814b** and a cover portion **2814a**. In this embodiment of the present invention, the cover portion **2814a** may further contain one or more non-threaded protrusions **2821** that rotate 90 degrees to go from an unlocked position to a locked position. The locked position of the cover portion **2814a** will allow the non-threaded protrusions to engage a complimentary non-threaded recessed undercut to retain the entirety of the hosel hole cover **2814** within the hosel hole **2818**.

It should be noted that most of the embodiments discussed here aims to create a releasable hosel hole cover, however, all of these embodiments may include glue to make the hosel hole cover stay within the hosel hole, removing the ability to remove the hosel hole cover without departing from the scope and content of the present invention.

Other than in the operating example, or unless otherwise expressly specified, all of the numerical ranges, amounts, values and percentages such as those for amounts of materials, moment of inertias, center of gravity locations, loft, draft angles, various performance ratios, and others in the aforementioned portions of the specification may be read as if prefaced by the word "about" even though the term "about" may not expressly appear in the value, amount, or range. Accordingly, unless indicated to the contrary, the numerical parameters set forth in the above specification and attached claims are approximations that may vary depending upon the desired properties sought to be obtained by the present invention. At the very least, and not as an attempt to limit the application of the doctrine of equivalents to the scope of the claims, each numerical parameter should at least be construed in light of the number of reported significant digits and by applying ordinary rounding techniques.

Notwithstanding that the numerical ranges and parameters setting forth the broad scope of the invention are approximations, the numerical values set forth in the specific examples are reported as precisely as possible. Any numerical value, however, inherently contains certain errors necessarily resulting from the standard deviation found in their respective testing measurements. Furthermore, when numerical ranges of varying scope are set forth herein, it is

contemplated that any combination of these values inclusive of the recited values may be used.

It should be understood, of course, that the foregoing relates to exemplary embodiments of the present invention and that modifications may be made without departing from the spirit and scope of the invention as set forth in the following claims.

What is claimed is:

1. A golf club head comprising:
a body portion further comprising a crown portion, a sole portion, a heel portion, and a toe portion;
a hosel region located near a heel portion of said golf club head, said hosel region further comprising:
an upper end having a releasable hosel mechanism;
a lower end having a hosel hole, said hosel hole further comprising:
a one or more non-threaded recessed undercuts along a side wall of said hosel hole,
a hosel hole cover, adapted to substantially cover an entirety of an internal surface of said hosel hole, and a retention mechanism, adapted to secure said hosel hole cover to said golf club head, wherein said retention mechanism comprises one or more non-threaded protrusions,
wherein said one or more non-threaded protrusions are adapted to engage said one or more non-threaded recessed undercuts to secure said hosel hole cover to said golf club head,
wherein at least a portion of said hosel hole cover is deformable, and
wherein said hosel hole cover bends to allow access to said hosel hole by disengaging at least one of said one or more non-threaded protrusions from said one or more non-threaded recessed undercuts.
2. The golf club head of claim 1, wherein said bending of said hosel hole cover maintains the engagement of at least one of said one or more non-threaded protrusions with at least one of said one or more non-threaded recessed undercuts.
3. The golf club head of claim 2, wherein said hosel hole cover further comprises a receptacle adapted to receive a tool, wherein said tool facilitates the bending of said hosel hole cover.
4. The golf club head of claim 2, wherein said hosel hole cover further comprises:
a base piece made out of a non-deformable rigid material, and
a cover piece made out of a deformable polymeric material.
5. The golf club head of claim 4, wherein said bending of said hosel hole cover is isolated within said cover piece of said hosel hole cover.
6. The golf club head of claim 5, wherein said bending of said hosel hole cover further comprises a receptacle opening, adapted to receive said retention mechanism,
said receptacle opening has a surface area of between about 55 mm² to about 300 mm².
7. The golf club head of claim 6, wherein said surface area of said receptacle opening has an area of between about 65 mm² to about 200 mm².
8. The golf club head of claim 7, wherein said surface area of said receptacle opening has an area of about 90 mm².
9. A golf club head comprising:
a body portion further comprising a crown portion, a sole portion, a heel portion, and a toe portion;
a hosel region located near a heel portion of said golf club head, said hosel region further comprising;

21

an upper end having a releasable hosel mechanism; a lower end having a hosel hole, said hosel hole further comprising;
 a one or more non-threaded recessed undercuts along a side wall of said hosel hole,
 a hosel hole cover, adapted to substantially cover an entirety of an internal surface of said hosel hole, and a retention mechanism, adapted to secure said hosel hole cover to said golf club head, wherein said retention mechanism comprises one or more non-threaded protrusions,
 wherein said one or more non-threaded protrusions are adapted to engage said one or more non-threaded recessed undercuts to secure said hosel hole cover to said golf club head,
 wherein at least a portion of said hosel hole cover is deformable, and
 wherein said hosel hole cover bends to allow access to said hosel hole by disengaging at least one of said one or more non-threaded protrusions from said one or more non-threaded recessed undercuts,
 wherein said hosel hole cover further comprises a receptacle opening, adapted to receive said retention mechanism,
 said receptacle opening has a surface area of between about 55 mm² to about 300 mm².

22

10. The golf club head of claim 9, wherein said surface area of said receptacle opening has an area of between about 65 mm² to about 200 mm².
11. The golf club head of claim 10, wherein said surface area of said receptacle opening has an area of about 90 mm².
12. The golf club head of claim 9, wherein said bending of said hosel hole cover maintains the engagement of at least one of said one or more non-threaded protrusions with at least one of said one or more non-threaded recessed undercuts.
13. The golf club head of claim 12, wherein said at least one or more non-threaded protrusions that is disengaged from said at least one or more non-threaded recessed undercut and said at least one or more non-threaded protrusion that remains engaged from said at least one or more non-threaded recessed undercut are located at opposite ends of said hosel hole cover.
14. The golf club head of claim 13, wherein a number of said at least one or more non-threaded protrusions that is disengaged from said one or more non-threaded recessed undercuts is lower than said at least one or more non-threaded protrusions that remains engaged from said one or more non-threaded recessed undercuts when said hosel hole cover is bent away to allow access to said hosel hole.
